STITCH SEPARATING MACHINE

Corwin W. Baker, Hamilton, Mass., assignor to
United Shoe Machinery Corporation, Flemington, N. J., a corporation of New Jersey

Application March 27, 1952, Serial No. 278,915

10 Claims. (Cl. 12--41)

1

This invention relates to stitch separating machines and it is herein disclosed as embodied in a machine which, except as otherwise shown and described, is like the machine disclosed in United States Letters Patent No. 2,558,725, granted July 3, 1951, upon my application. Said Letters Patent contain claims generic to the present invention.

The present invention consists in the novel features hereinafter described, reference being had to the accompanying drawings which illustrate one embodiment of the same selected for purposes of illustration, and the said invention is fully disclosed in the following description and claims.

In the accompanying drawings.

Fig. 1 is a side elevation of the upper portion of an illustrative machine embodying the invention;

Fig. 2 is a front elevation of the parts shown in Fig. 1;

Fig. 3 is a plan view of the parts shown in Figs. 1 and 2;

Fig. 4 is a side elevation in section of a combined valve and pump shown in Figs. 1 and 2;

Fig. 5 is a front elevation in section of the member shown in Fig. 4;

Figs. 6 to 12 inclusive are side elevations of mechanisms shown in the preceding figures;

Fig. 13 is an angular view of a mechanism for adjusting the feed stroke of the feed dog;

Fig. 14 is an angular view of the presser feet and their supports; and

Fig. 15 is a diagrammatic showing of the fluid pressure and lubricating systems.

The work-engaging instrumentalities of the illustrated machine consist of a stitch separating tool and feed dog 20 (Figs. 1, 2, 3 and 9), an indenting tool 22 (Figs. 2, 3 and 10), a pair of presser feet 24 and 26 (Figs. 1, 2, 3 and 11) and a worktable 28 (Figs. 1 and 3). The supporting structure of the machine comprises a column in which is mounted a heightwise-adjustable post (like the column and post shown in Letters Patent No. 2,558,725 above referred to); and on the post is secured a box-like head 30 surmounted by a housing 32 having a lid 34.

The various operating instrumentalities of the machine are all driven by eccentrics secured upon a shaft 36 (Figs. 1 and 3) journaled in ball bearings 38 which are mounted in the housing 32. The shaft 36 carries a pulley 40 through which it is driven by any suitable source of power, and the shaft can be turned by a handwheel 42 for purposes of inspection and adjustment.

The several functions of the feed dog 20 are to

find the intervals between the stitches, to feed the shoe, to separate the stitches, and to effect a preliminary indentation at each stitch interval. The feed dog 20 is a blade-like member having an orbital movement resulting from components of oscillation in the direction of feed and also heightwise, the feed dog being down in engagement with the workpiece during its advance stroke and up out of engagement with the workpiece during its retraction.

The feed dog 20 (Fig. 9) is secured upon the forward end of an arm 44 having a yoke-shaped rear portion comprising a pair of spaced bearings 46 by which the arm is pivotally mounted upon a pin 48 to enable the feed dog to oscillate horizontally in the direction of feed. The pin 48 is secured in a sleeve 50 extending between the bearings 46 and having a boss in which is formed a bearing for a horizontally extending supporting pin 52 about which the sleeve 50 and the arm 44 can swing heightwise to enable the feed dog 20 to be moved up and down. The pin 52 is supported by a pair of spaced stationary bracket arms 54 secured to the housing 32.

The means for oscillating the feed dog 20 in the direction of feed comprises a link 56 (see also Figs. 3 and 13) having one end pivotally connected by a ball joint 58 to the arm 44 and its other end pivotally connected by a ball joint 60 (formed on the upper portion of a pin) to an ear 62 extending horizontally from a dovetail slide 64. This slide 64 engages an arcuate guideway formed in a rocking bracket or lever 66 having a horizontal flange 68 integral with a hub 70. This hub 70 is secured upon the top of an upright shaft 72 which rocks freely in upper and lower supporting bearings 74 (Figs. 7 and 2) and serves as a fulcrum for the lever constituted by the bracket 66. Extending from the hub 70 is a rocker arm 76 which is pivotally connected by a ball joint 78 to the forward end of an eccentric rod 80 (see also Fig. 7) having a strap 82 which engages an eccentric 84 on the shaft 36. The strap 82 and the eccentric 84 have complementary spherical engaging surfaces to enable the rod 80 to accommodate the displacement resulting from the arcuate movement of the ball joint 78. A counterweight 86 on the shaft 36 and secured to the eccentric 84 helps to balance the dynamic forces acting locally on the shaft. It is evident from the foregoing description that each revolution of the shaft 36 will result in one complete component of oscillation of the feed dog 20 along the path of feed.

Adjustment of the slide 64 in its arcuate guide-

way serves to vary the length of the feed stroke of the feed dog 20. In order to insure that the feed dog 20 will always terminate its advancing feed stroke at the same point regardless of such adjustment, the arcuate guideway of the bracket 66 is so designed as to have for its axis a vertical line passing through the center of the ball joint 58 when the eccentric 84 is in its most rearward position and the feed dog is in its most advanced position. It is evident that adjustment of the slide 64 along a path concentric with the ball joint 58 when the latter occupies its most advanced position will not change that position. An initial adjustment of the most advanced position of the feed dog 20 in setting up the machine, or readjustment when necessary, can be effected by a turnbuckle included in the link 56 as shown in the drawings.

To enable the length of the feed stroke of the feed dog 20 to be varied by adjustment and to be maintained in a desired position of adjustment, there is provided a mechanism shown in Figs. 1, 2, 8 and 13. This mechanism comprises an adjusting link 88 pivotally connected at one end, by the same pin that carries the ball joint 60, to the ear 62 and at its opposite end to a crank arm 90 extending from a sleeve 92 freely rotatable upon a stationary pin 94 depending from the lid 34. Extending from the sleeve 92 is another crank arm 96 by which the sleeve can be rocked. A link 98 has one end pivotally connected to the crank arm 96 and its other end pivotally connected to a pin 100 which depends eccentrically from the lower end of an upright shaft 102 extending up through, and journaled in, a bearing 104 depending from the lid 34. Upon the upper end portion of the shaft 102 is secured a hub 106 of a disk 108. A handle 110 on the forward end of an arm 112 facilitates turning of the disk 108, the arm being fulcrumed upon a horizontal pin 114 extending between ears 116 upstanding from the disk. It is evident that the handle 110 and the connections therefrom are manual means for operating the crank arms 90 and 96, and that said crank arms together with the sleeve 92, therefore, constitute a manually operated adjusting lever fulcrumed upon the stationary pin 94 and pivotally connected to an end of the adjusting link 88. The arm 112 has a downward extension 118 which pushes against an end of a brake 119 slidably radially in a bore in the disk 108 and having its other end tapered for wedging engagement with an annular groove formed in the periphery of a stationary disk 120 coaxial with the disk 108. A compression spring 122 normally holds the handle 110 up, with the extension 118 in braking position. A stationary pointer 124 cooperates with graduations on the periphery of the disk 108 to indicate positions of the disk corresponding to various adjustments of the length of the feed stroke of the feed dog 20. Depression of the handle 110 releases the brake 119 and permits the disk 108 and shaft 102 to be turned, operating through the linkages above described to move the slide 64 in its arcuate guideway toward or from the axis of the fulcrum shaft 12 to vary the extent to which the feed dog 20 will be retracted on its back-feed movement. In the illustrated machine the center of the ball joint 60, during adjustment, moves in an arcuate path which intersects the axis of the fulcrum shaft 12, and travel of the feed dog can be varied from about zero to, for example, about one quarter of an inch.

Heightwise movement of the feed dog 20 is effected by mechanism comprising a lower toggle link 126 (Figs. 1, 3 and 9) pivotally connected at one end by a ball joint 128 to the arm 44. The opposite end of the lower link 126 engages a spherical surface formed on a horizontal toggle pin 130 which serves as a pivotal connection between the lower link and an upper toggle link in the form of two parallel arms 132 (see also Fig. 2) extending integrally from a sleeve 134. A stationary horizontal pin 136, supported at its end portions by ears 138 extending from a bracket 140, serves as a bearing about which the sleeve 134 and the arms 132 can turn. Movement is imparted to the toggle 126, 132 by an eccentric rod 142 pivotally connected at one end to the toggle pin 130 and having at its other end a strap 144 in driving engagement with an eccentric 145 on the shaft 36. A counterweight 146 maintains the shaft 36 in dynamic balance at this locality.

The indenting tool 22 is similar to the indenting tool 22 of the machine disclosed in said Letters Patent No. 2,558,725 and it is similarly mounted on a connecting rod 148 (Fig. 10) which corresponds to the rod 106 of said patented machine and which is driven by an eccentric 150 on the shaft 36. A counterweight 152 maintains the shaft 36 in dynamic balance at this locality. The movements of the indenting tool 22 are controlled by an arm 154 corresponding to the arm 110 of said patented machine. In the present machine the arm 154 is pivotally mounted upon an eccentric portion of a shaft 156 rotatable in a bearing lug 158 extending from the housing 32. The shaft 156 can be turned for purposes of adjustment to vary the depth to which the indenting tool 22 descends. A crank handle (not shown) outside the housing 32 facilitates adjustment, and can be latched in adjusted position by a suitable detent.

The presser foot 24 (Figs. 2, 3, 11 and particularly 14) has a rearwardly extending dovetail shank which is clamped in a desired position of forward and rearward adjustment between a clamp 159 and a block 160 by a screw 162. The block 160 has a depending lug 164 which is clamped directly to a slide 166 by a screw 168. The slide 166 is movable in an undercut guideway 170 extending parallel to the feed of the work, that is, transversely of the machine. The guideway 170 is formed in a long irregularly shaped bracket 172 having bearing hubs 171 and 173 at its ends by which the bracket is journaled for swinging movement upon a stationary shaft 174 extending transversely of the machine and secured in sockets 176 integral with the housing 32.

The presser foot 24 can be adjusted in the direction of feed of the work by means comprising a sleeve 178 integral with the block 160 and slidably on the shaft 174. Formed in the sleeve 178 is an annular groove which is engaged by a yoke 180 swiveled upon a pin 182 which depends from an adjusting link 184 (see also Fig. 2). The opposite end of the link 184 (see also Fig. 6) is pivotally connected by a pin 186 to an extension 188 of a yoke-shaped lever 190 which is fulcrumed on a stationary vertical shaft 192. A bracket 194 secured by screws 196 to an extension of one of the arms 54 has an overhanging sleeve 198 in which the shaft 192 is held by a set screw 200. The two horizontal arms of the yoke-shaped lever 190 have bearing hubs

202 which engage the shaft 192 above and below the sleeve 198. Swinging movement of the lever 198 about its fulcrum pin 192 is effected by a link 204 (see also Fig. 13) having one end pivotally connected to the lever by a pin 206. The opposite end of the link 204 is pivotally connected by a pin 208 to an arm 210 extending from the sleeve 92. It is evident that the same movement of the handle 110 which adjusts the length of stroke of the feed dog 20 will serve also to adjust the position, in the direction of feed, of the presser foot 24 and that the displacement of the presser foot 24 from the presser foot 26 will be greater for a long feed stroke than for a short feed stroke.

The presser foot 26 has a rearwardly extending dovetail shank which is clamped in a desired position of forward and rearward adjustment between a clamp 211 and a block 212 by a screw 214. The block 212 has a depending dovetail shank 215 which is clamped for heightwise adjustment between a clamp 216 (which has a beveled face engaging a bevel of the shank 215) and a block 217 (having a beveled face which engages the other bevel of the shank 215).

Clamping pressure is effected by a screw 218 extending through the clamp 216 and threaded into a slide 219 like the slide 166 and integral with the block 217.

The slide 219 is supported for adjustment transversely of the machine in the following manner. The bracket 172 has a forwardly extending flange 220 (Fig. 14) and an upwardly extending flange 221 which together form the lower undercut portion of the guideway 170. Both these flanges 220 and 221 are cut away at the locality of the slide 219, their place being taken by an L-shaped clamp 222 which, in effect, may be said to constitute a continuation of the lower undercut portion of the guideway 170. The L-shaped clamp 222 is urged into clamping engagement with the lower edge portion of the slide 219 by two screws 224 which are tightened after the slide has been adjusted transversely of the machine. The base of the guideway 170 is formed by a vertical flange 226 (Fig. 14) which continues to the left in back of the slide 219 and which, at that locality, has a downward extension 227 (Figs. 1 and 2) into which the screws 224 are threaded. The upper portion of the slide 219 engages the upper undercut portion of the guideway 170 which continues to the left.

The bracket 172 is oscillated about its trunnion bearings on the shaft 174 to raise and lower the presser feet 24 and 26 in timed relation to the movements of the feed dog 20 and the indenting tool 22. To this end the bracket 172 has an arm 228 (Figs. 14, 11, and 2) extending upwardly and rearwardly from the integral hub 171. A connecting rod 232 pivotally connected at one end by a pin 234 to the arm 228 and having at its other end an eccentric strap 236 engaging an eccentric 238 on the shaft 36 transmits rocking movement to the bracket 172. A counterweight 240 maintains the shaft in dynamic balance at this locality.

The worktable 28 is mounted indirectly upon a head 242 (Fig. 1) corresponding to the member 266 of the machine disclosed in Letters Patent No. 2,558,725 above mentioned. The arrangements for adjusting the worktable 28 with respect to the head 242 are similar to corresponding arrangements disclosed in said Letters Patent and need not be described herein. The head 242 constitutes the upper portion of a

plunger 244 which is guided for heightwise movement in a hydraulic cylinder comprising a bore 246 formed in a stationary block 248 secured to the machine head 30. A vent normally closed by a plug 249 can be opened to release air trapped below the plunger 244.

The worktable 28 is yieldingly urged up during each feeding movement of the work; and it is locked against heightwise movement during each operation of the indenting tool 22 so as to afford a rigid support to the work while the work is being indented. Such control of the worktable 28 is obtained by a fluid pressure system shown in Figs. 1, 2, 4 and 5 and diagrammatically illustrated in Fig. 15. This fluid pressure system comprises a pipe 250 (Fig. 1 shows the entire pipe and Fig. 2 shows it as broken away at its lower portion) communicating at one of its ends with the bottom of the bore 246 and at its other end with an annular port 252 (Fig. 5) formed in a stationary sleeve 254 which serves as a lining for a heightwise bore in a block 256 secured to and depending from the base of the housing 32. Formed in the sleeve 254 above the port 252 is another annular port 258 communicating with one end of a pipe 260, the other end of which pipe is connected, through a T-fitting 262, to a pipe 264 which leads to the bottom of a hydraulic accumulator 266 containing liquid in the form of lubricating oil and air under pressure. This accumulator may be of the type shown in Fig. 2 of United States Letters Patent No. 2,578,959, granted December 18, 1951, upon the application of Joel E. Yarborough. A tire valve 268 enables the accumulator 266 to be charged with air. It is evident that when the ports 252 and 258 are both open, the air pressure in the accumulator is transmitted through the oil in the pipes 264, 260 and 250 to the oil in the bore 246 below the plunger 244 to urge the plunger and the worktable 28 yieldingly up.

In the illustrated machine the port 258 is always open and the port 252 is intermittently closed by a valve plunger 270 reciprocating in the sleeve 254 and connected by a stem 272 to a guide plunger 274 engaging the sleeve above the valve plunger. The upper end of the guide plunger 274 is pivotally connected by a pin 276 (Fig. 12) to the lower end of a connecting rod 278 having an eccentric strap 280 which engages an eccentric 282 on the shaft 36. A counterweight 284 maintains the shaft 36 in dynamic balance at this locality.

The eccentric 282 is timed to open the valve 252 to admit accumulator pressure to the worktable supporting plunger 244 during the feeding movements of the work and to close the valve 252 and thereby hydraulically lock the worktable 28 against heightwise movement during the indenting stroke of the tool 22. The yielding upward thrust of the plunger 244 permits the worktable 28 to yield down under the pressure of the descending presser feet 24 and 26; and when the presser feet come down into work clamping position, the valve 252 closes to lock the worktable in the heightwise position it has then assumed.

The reciprocating valve plunger 270 is utilized also to pump oil through a lubricating system and to recharge the accumulator 266 with oil to restore or maintain the accumulator pressure which otherwise might be diminished by oil leakage. To this end the sleeve 254 has formed in it an annular intake port 286 (Figs. 4 and 5)

below the port 252 and at such a level as to be opened when the plunger 270 is at the upper portion of its stroke. Descent of the plunger 270 closes the intake port 286 and forces the oil beneath the plunger down through the open lower end (which serves as the outlet port) of the sleeve 254 and into a conduit 288 threaded into and leading down from the lower end of the block 256. Communicating with the intake port 286 is a duct 290 (Fig. 4) formed in the block 256. The lower portion of the housing 32 serves as a sump or reservoir from which lubricating oil is drawn through a pipe 292 to the duct 290 and thence through the port 286 into the space beneath the plunger 270. From there the oil is forced down through the conduit 288 and through a check valve 294 (Fig. 1) which permits the oil to flow down but not up. From the check valve 294 the oil flows through a conduit 296 and through a filter 298 into a T-fitting 300; and it passes from a branch of the T-fitting 300 through a conduit 302 to a pressure-regulating valve in the form of a relief valve 306 which is set to maintain a pressure of from about fifty to sixty pounds per square inch on its intake side. The oil which is released by the relief valve 306 passes through a pipe 308, a duct 307 (Fig. 4) formed in the wall of the block 256, and thence through a pipe 309 to a lubricating system, preferably of the type which drips the oil upon those portions of the operating mechanism which require it. The used oil returns to the sump formed by the bottom of the housing 32 and is recirculated. A pressure gage 310 communicating with the conduit 302 enables the operator to set the relief valve 306 to the desired pressure. A needle valve 312 between the pressure gage 310 and the conduit 302 dampens the surge of the oil pressure upon the pressure gage.

The accumulator pressure is maintained, or is restored if diminished by oil leakage, by connections comprising a conduit 314 connecting the T-fittings 300 and 262. Interposed in the conduit 314 is a needle valve 316 which is usually opened upon starting the machine to replenish the accumulator 266 with oil if any oil has been lost by leakage overnight. After the accumulator pressure has thus been restored to normal, the valve 316 can be partly closed to dampen the surge of the pump or, if desired, the valve can be completely closed. A pressure gage 318 interposed between the valve 316 and the T-fitting 262 indicates the accumulator pressure at all times.

To facilitate entry and removal of work a treadle mechanism (not shown) is connected by a rod 320 (Fig. 1) to the head 242. Depression of the treadle in opposition to the accumulator pressure serves to lower the worktable 28. The height to which the worktable can rise when not limited by the presence of a workpiece is determined by an adjustable stop in the treadle mechanism.

The operation of the work-engaging members is substantially like that of the corresponding members of the machine disclosed in said Letters Patent No. 2,558,725 and will now be described. To introduce a workpiece into the machine, the operator bears down upon a treadle to depress the rod 320 and thereby to lower the worktable 28. The rapid periodic opening of the valve port 252 permits the operator thus to pull the worktable 28 down against the pressure of the accumulator 266 so that he can insert the marginal portion of the shoe bottom between the work-

table and the presser feet 24 and 26. Release of the treadle permits the fluid pressure mechanism to raise the worktable 28 to its working position. The various operating instrumentalities of the machine will then at once begin to work upon the shoe, regardless of whatever particular phase they may happen to be in.

Suppose, for example, that the valve plunger 270 is at the top of its up stroke, closing the port 252 and thus holding the worktable 28 momentarily locked against heightwise movement. The presser feet 24 and 26 will be down in work-clamping position; the indenting tool 22 will be down at about its lowest point to indent the welt; the feed dog 20 will be up out of contact with the work and will be moving in a direction opposite to that in which it feeds the work. As the shaft 36 rotates, the valve plunger 270 will descend and unlock the worktable 28; and it will also pump oil through the lubricating system and recharge the accumulator 266 with oil, or maintain the pressure therein, as has already been explained. During this rotation of the shaft 36, the indenting tool 22 will rise up out of the work and the presser feet 24 and 26 will rise immediately after the indenting tool; and the accumulator pressure will urge the worktable 28 up with the upper surface of the welt against the presser feet 24 and 26 until the descending feed dog 20 engages the work and holds it down. The feed dog, because of its overtravel, will engage the intermediate portion of a stitch and, as it moves in the direction of feed, will glide idly over the stitch until it engages a stitch interval, whereupon it will feed the work during the remaining portion of its feed stroke. The feed dog 20 not only separates the stitches but makes a preliminary indentation. At the end of its feed stroke it leaves the stitch interval at the precise point at which the indenting tool 22 will descend. The presser feet 24 and 26 will now begin to descend and, immediately after they are down, the valve plunger 270 will close the port 252 and lock the worktable with the work clamped against the presser feet. The indenting tool 22, which has been up and out of the way of the feed dog 20, will now descend to deepen the preliminary stitch indentation already formed in the stitch interval. As the indenting tool descends, it will be cammed by the adjacent inclined face of the presser foot 26 into the precise position for engagement in the stitch interval. This cycle will be repeated indefinitely until the entire portion of the sole margin to be treated has been operated upon at which time the operator will depress the treadle and withdraw the work from the machine.

Having thus described my invention what I claim as new and desire to secure by Letters Patent of the United States is:

1. In a stitch separating machine, a work feeding mechanism comprising a feed dog mounted for back and forth feeding movement, a lever having an arcuate guideway, a fulcrum for the lever, means for rocking the lever through a predetermined angle about its fulcrum, a slide movable toward and from said fulcrum along the arcuate guideway of the lever, a link for transmitting feeding movements of advance and retraction from the lever to the feed dog, a pivotal connection between the feed dog and one end of the link, a pivotal connection between the slide and the opposite end of the link, and means 75 for maintaining the slide in a position of adjust-

ment along the arcuate guideway, said arcuate guideway having for its axis a line passing through the first mentioned pivotal connection when the lever occupies its most advanced position in the direction of feed, such arrangement serving to enable adjustments of the slide along the guideway to vary the length of stroke of the feed dog while maintaining constant the position occupied by the feed dog at the end of its feeding stroke.

2. In a stitch separating machine, a work feeding mechanism comprising a feed dog adapted to enter between the outseam stitches of a shoe and there to exert a feeding force upon the shoe, a support on which the feed dog is mounted for back and forth movements in the direction of feed, a lever having an arcuate guideway, a fulcrum about which the lever can turn, a driven shaft, an eccentric on the shaft, a connecting rod driven by the eccentric for oscillating the lever about its fulcrum, a slide movable toward and from said fulcrum along the arcuate guideway of the lever, a link for transmitting feeding movements of advance and retraction from the lever to the feed dog, a pivotal connection between the feed dog and one end of the link, a pivotal connection between the slide and the opposite end of the link, and means for maintaining the slide in a position of adjustment along the arcuate guideway, said arcuate guideway having for its axis a line passing through the first mentioned pivotal connection when the lever occupies its most advanced position in the direction of feed, such arrangement serving to enable adjustments of the slide along the guideway to vary the length of stroke of the feed dog while maintaining substantially constant the position occupied by the feed dog at the end of its feeding stroke.

3. In a stitch separating machine, a work feeding mechanism comprising a feed dog mounted for back and forth feeding movement, a lever having a guideway, a slide in the guideway, a fulcrum for the lever, means for rocking the lever about its fulcrum, a link having pivotal connection at its ends to the slide and the feed dog for transmitting the rocking movement of the lever as feeding movement to the feed dog, an adjusting link pivotally connected at one end to the slide, a manually operated adjusting lever pivotally connected to the opposite end of the adjusting link to vary the position of the slide in its guideway toward and from said fulcrum and thereby to vary the length of the feed stroke of the feed dog, and a stationary fulcrum for said adjusting lever.

4. In a stitch separating machine, a worktable, a stitch separating tool for making indentations in the welt of a shoe on the worktable between the outseam stitches, means for raising and lowering the stitch separating tool to cause it to make such indentations, a feed dog adapted to enter between the stitches and there to exert a feeding force upon the shoe, a support upon which the feed dog is mounted for back and forth movement in the direction of feed, a lever having an arcuate guideway, a fulcrum about which the lever can turn, means for oscillating the lever through a predetermined angle about its fulcrum, a slide movable toward and from the fulcrum along the arcuate guideway of the lever, a link for transmitting movements of advance and retraction from the lever to the feed dog, a pivotal connection between the feed dog and one end of the link, a pivotal connection between the

slide and the opposite end of the link, said arcuate guideway having for its axis a line passing through the center of the first mentioned pivotal connection at the most advanced position of that connection in the direction of feed, such arrangement serving to enable adjustments of the slide along its guideway to vary the length of stroke of the feed dog while insuring that the feed dog at the end of its feeding stroke will occupy the position into which the stitch separating tool will subsequently be lowered, an adjusting link pivotally connected at one end to the slide, a manually operated adjusting lever pivotally connected to the opposite end of the adjusting link to vary the position of the slide in its guideway toward and from said fulcrum and thereby to vary the length of feed stroke of the feed dog, and a stationary fulcrum for the adjusting lever.

5. In a stitch separating machine, a worktable, a presser foot engageable with the welt of a shoe to hold the margin of the shoe bottom against the worktable, a feed dog engageable with the welt of the shoe to feed the shoe step by step, a lever having a guideway, a slide in the guideway, a fulcrum for the lever, means for rocking the lever about its fulcrum, a link having pivotal connection at its ends to the slide and the feed dog for transmitting the rocking movement of the lever as feeding movement to the feed dog, an adjusting link pivotally connected at one end to the slide, a manually operated adjusting lever pivotally connected to the opposite end of the adjusting link to vary the position of the slide in its guideway toward and from said fulcrum and thereby to vary the length of the feed stroke of the feed dog, a stationary fulcrum for said adjusting lever, a holder for the presser foot, a guide upon which the presser foot holder is mounted for adjustment in the direction of feed, an adjusting link having a pivotal connection at one of its ends with said presser foot holder, and connecting means between said adjusting lever and the opposite end of the second-mentioned adjusting link whereby movement of the adjusting lever to vary the length of feed stroke of the feed dog serves also to adjust the position of the presser foot in the direction of feed.

6. In a machine for operating on shoe parts, a worktable, a tool, means for oscillating the tool heightwise to cause it to operate upon a work piece on the worktable, a hydraulic cylinder, a plunger in said cylinder for supporting the worktable, an accumulator containing liquid and air under pressure, a passageway for liquid between the hydraulic cylinder and the accumulator whereby the air pressure in the accumulator yieldingly acts upon the plunger to urge the worktable up, a presser foot engageable with the work piece to hold it down against the upward thrust of the worktable, a valve interposed in said passageway, connections from said oscillating means for closing the valve to hold the worktable locked during the down stroke of the tool and for opening the valve to enable the fluid pressure of the accumulator to press the worktable up yieldingly during the up stroke of the tool, a reservoir for liquid, a pump for charging the accumulator from the reservoir, said pump having a plunger directly connected to and movable in unison with the valve, and a regulating valve for controlling the pressure to which the pump can charge the accumulator.

7. In a machine for operating on shoe parts, a worktable, a tool, means for oscillating the tool heightwise to cause it to operate upon a work

piece on the worktable, a hydraulic cylinder, a plunger in said cylinder for supporting the worktable, an accumulator containing liquid and air under pressure, a passageway for liquid between the hydraulic cylinder and the accumulator whereby the air pressure in the accumulator yieldingly acts upon the plunger to urge the worktable up, a presser foot engageable with the work piece to hold it down against the upward thrust of the worktable, a valve cylinder interposed in said passageway, said valve cylinder having a port which can be closed to retain liquid within the hydraulic cylinder to lock the worktable in its up position and which can be opened to unlock the worktable and enable it to be supported yieldingly by the air pressure in the accumulator, a valve plunger within the valve cylinder for controlling said port, connections from said tool oscillating means for reciprocating the valve plunger to close the port and thereby hold the worktable locked during the down stroke of the tool and to open the port and thereby enable the fluid pressure of the accumulator to press the worktable up yielding during the up stroke of the tool, a reservoir for liquid, a pump for charging the accumulator from the reservoir, said pump having a cylinder which is an extension of said valve cylinder, said valve plunger serving also as a plunger for said pump, and means for regulating the pressure to which the pump can charge the accumulator.

8. In a machine for operating on shoe parts, a worktable, a tool, means for oscillating the tool heightwise to cause it to operate upon a work piece on the worktable, a hydraulic cylinder, a plunger in said cylinder for supporting the worktable, an accumulator containing oil and air under pressure, an oil passageway between the hydraulic cylinder and the accumulator whereby the air pressure in the accumulator yieldingly acts upon the plunger to urge the worktable up, a presser foot engageable with the work piece to hold it down against the upward thrust of the worktable, a valve cylinder interposed in said passageway, said valve cylinder having a port which can be closed to retain oil within the hydraulic cylinder to lock the worktable in its up position and which can be opened to unlock the worktable and enable it to be supported yieldingly by the air pressure in the accumulator, a valve plunger within the valve cylinder for controlling said port, connections from said tool oscillating means for reciprocating the valve plunger to close the port and thereby hold the worktable locked during the down stroke of the tool and to open the port and thereby enable the fluid pressure of the ac-

cumulator to press the worktable up yieldingly during the up stroke of the tool, a lubricating device, a reservoir for used oil from said lubricating device, a pump for recirculating oil from the reservoir to the lubricating device and for recharging the accumulator, said pump having a cylinder which is an extension of said valve cylinder and utilizing for its plunger the said valve plunger, a passageway connecting the pump outlet to the accumulator, and a pressure regulating valve arranged to open only at a predetermined intake pressure, said pressure regulating valve having its intake connected to the last-mentioned passageway and its outlet connected to the lubricating device.

9. In a stitch separating machine, a worktable mounted for heightwise movement, a feed dog engageable with the welt of a shoe on the feed table to feed the shoe step by step, means for imparting to the feed dog feeding movements of advance and retraction, means for yieldingly urging the worktable up during the advance feeding movement of the feed dog, a presser foot engageable with the welt to hold the welt down against the upward thrust of the worktable, a hydraulic cylinder, a plunger in the cylinder for supporting the worktable, a conduit connecting the cylinder to a supply of liquid, a valve cylinder having a port which can be closed to retain liquid within the hydraulic cylinder to lock the worktable positively in its up position and which can be opened to unlock the worktable and enable it to be supported yieldingly by the urging means, a valve plunger within the valve cylinder, means for reciprocating said valve plunger relatively to said port to cause the worktable to be locked during the retraction of the feed dog and unlocked during the advance of the feed dog, a system for lubricating moving parts of the machine, and a pump comprising said valve plunger and said valve cylinder for supplying oil to said lubricating system.

10. In a stitch indenting machine, an indenting tool, a connecting rod, means for mounting the indenting tool on the connecting rod, rotary means for driving the connecting rod, a link having at one end a pivotal connection to the connecting rod for controlling the movement of the indenting tool caused by the rotary means, and a shaft having an eccentric portion upon which the other end of said link is pivotally mounted, said shaft being rotatable to adjust the position to which the indenting tool descends at the end of its down stroke.
